J. Jenkins,

Corn Planter:

No. 95,906.

Patented Oct. 19. 1869.

Geo. E. Mean.
Attorney

United States Patent Office.

JESSE JENKINS, OF ANDREW COUNTY, MISSOURI, ASSIGNOR FOR ONE-HALF TO ABRAM DOBBS, OF SAME PLACE.

Letters Patent No. 95,906, dated October 19, 1869.

IMPROVEMENT IN CORN-PLANTER AND CULTIVATOR.

The Schedule referred to in these Letters Patent and making part of the same.

To all whom it may concern:

Be it known that I, JESSE JENKINS, of Andrew county, in the State of Missouri, have invented a new and useful Improvement in a Planter, Cultivator, and Roller, combined; and I do hereby declare that the following is a full, clear, and exact description of the same, reference being had to the accompanying drawings, and letters of reference marked thereon, making a part of this specification, in which—

Figure 1 is a plan view, and

Figure 2 is a longitudinal central vertical section.

To enable those skilled in the art to make and use my invention, I now proceed to describe its construction and operation.

Similar letters in the drawings refer to like parts.

This invention consists in connecting, with the drop-apparatus of a planter, a peculiar mechanism for disconnecting it from its motive-power, at any time it may be required to arrest the deposit of seed. Also, in connecting with the driving-wheel of a planter-apparatus, a mechanism for preventing said wheel from revolving during the turning of corners, so as to arrest the deposit of seed at such times. Also, in the general combination of the several above-named parts.

In the drawings—

a a are the seed-boxes, through which play the double drop-slides *a'*, between each pair of which, at the forward end, is pivoted the plate *a''*, the latter being joined, by connecting-rods *b*, with the cranks *b'*, in the shaft *b*, the latter being rotated, and consequently giving motion to the slide, by means of the cog-gearing *d d'*, the wheel *d* fastened upon the end of the said shaft, and the wheel *d'*, rigidly connected with the main wheel *A*.

Between the wheel *d'* and the crank *b'*, nearest it, the shaft passes across the pivoted standard *c*, and lies in a groove in the same.

The standard is pivoted, as seen in fig. 2, to the frame *A*, by means of an offset, *o*, extending down into a slot in the frame.

A handle, *c''*, rises from the standard *c*, and passes through a slot made lengthwise of the horizontal guide-frame *c'*, which slot has small offsets *s* in one side, in either of which the spring-plate *c''* fits, which spring-plate is attached, at its lower end, to the standard *c*. The conjoint operation of the offset and spring locks the standard.

On removing the spring from the offset, there is nothing to prevent throwing the standard *c* back on its pivot *o*, and thus raising the shaft *b*, till the cog-wheel *d'* is separated from the cog-wheel *d*, when the operation of the planting-apparatus is arrested, until such time as the cog-wheels *d d'* are brought together again, by restoring the lever to its former position.

The pivoted standard is intended especially for use

when, in moving straight forward, it is desirable to prevent the planting-apparatus from acting, as in going from place to place in fields or on roads.

In fig. 1, *h* is an iron rod, passing through the frame-work *A*, opposite the rim of the wheel *A*.

There is a hole in the latter, into which the end of the rod *h* may be made to enter, by moving in the proper direction the lever *h'*, pivoted across the axle *A*, which movement is effected by the handle *h''*, pivoted in the inner end of the beam *h*, projecting inward from the side of the frame.

The lower end of the handle is jointed to the rear end of the lever *h'*, and its movement from right to left causes the rod *h* to enter the wheel and stop its revolution.

The shaft *b* ceases to revolve when the wheel *A* does, and the stoppage of the planter-apparatus follows.

The brake-mechanism is designed to be used in turning corners, when it is not necessary that the wheel *A* should rotate.

The frame *A* has a shaft, *D*, attached to its rear end by slotted holders *i*, so that the shaft can rise or fall, as necessary.

Rollers *D'* are placed upon the shaft, exactly in the rear of the seed-boxes *a* and cultivator-shovels *r r*, which prepare the drill and cover the seed. The rollers follow, and smooth down the ridge.

C C' are shafts, placed crosswise of the frame, to which shafts the shovels *r r* are connected.

B is another shaft, in the front part of the frame, having arms *k* projecting downward from its lower side, to which arms are jointed the front ends of the rods *m n*, the latter being jointed at their rear ends to the shovel-supports. By rotating the shaft *B*, the shovels are lifted out of or returned into the soil.

What I claim as new, and desire to secure by Letters Patent, is—

1. The combination of the seed-box *a*, slide *a'*, shaft *b*, with the pivoted standard *c''*, spring *c''*, and slotted guide-frame *c'*, all arranged and operating substantially as described.

2. The combination, with the seeder-frame, of the lever *h*, rod *h*, and handle *h''*, in the manner and for the purpose set forth.

3. The combination of shaft and roller *D D'* with the shafts and shovels *C C' r r*, controlling-shaft *B*, planter-apparatus *a a'*, crank-shaft *U*, disconnecting-apparatus *c c' c''*, and brake-mechanism *h h'' h''*, all arranged and operating in the manner explained.

JESSE JENKINS.
